CLAIM

The ornamental design for a front cowling of a multi-purpose vehicle, as shown and described.

DESCRIPTION

FIG. 1 is a perspective view of a front cowling of a multi-

purpose vehicle showing the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is bottom plan view thereof.

The broken lines shown in the drawings are for the purpose of illustrating environmental structure that forms no part of the claimed design.
